UNITED STATES PATENT OFFICE

NICHOLAS SAMANTAS, OF SAN FRANCISCO, CALIFORNIA, ASSIGNOR OF ONE-HALF TO
CHARLES F. JOHNSTON, OF OAKLAND, CALIFORNIA

COMB

Application filed March 17, 1931. Serial No. 523,345.

An object of my invention is to provide a comb which is designed especially for use with hair waving machines although it can be used independently if desired.

5 The comb consists of a U-shaped member provided with a plurality of teeth, this member being hinged to a needle and swingable toward the needle so that the U-shaped teeth will straddle it. A spring normally holds 10 the comb portion away from the needle.

A further object of my invention is to provide a device of the type described in which 15 two needles are hinged together and may be swung toward each other, a spring being employed for moving the needles apart when they are manually released.

20 A further object of my invention is to provide a device of the type described which is extremely simple in construction and which 25 is durable and efficient for the purpose intended.

Other objects and advantages will appear as the specification proceeds, and the novel 30 features of the device will be particularly 35 pointed out in the claims hereto annexed.

My invention is illustrated in the accompanying drawing, in which:

Figure 1 is a side elevation of the device;

Figure 2 is a section along the line 2—2 of

30 Figure 1; and

Figure 3 is a section along the line 3—3 of Figure 1.

In carrying out my invention I provide a 35 rod or needle 1 which is inserted in a sleeve portion 2 of a supporting member 3. A comb indicated generally at 4 is pivoted to the support 3 at 5 and a needle indicated generally at 6 is pivotally secured to the support 3 at 7.

The comb 4 has a U-shaped portion 8 40 (see Figure 3) with teeth 9 formed therein. The comb may be manually swung toward the needle 1 and against the force of a spring 10 so that the teeth 9 will enclose the needle 1 as shown in Figure 3. As soon as the comb 4 is released the spring 10 will swing it back 45 into the full line position as shown in Figure 1.

The needle 6 is carried by an arm 11 and 50 the other end of the spring 10 bears against

this arm for swinging it into the position shown.

From the foregoing description of the various parts of the device the operation may be readily understood.

After all of the protectors or clips have 55 been placed in the hair and the hair has been blocked and wet with the usual lotion, the comb is taken between the thumb and index finger, and the hair from one clip is 60 placed between the comb and the needle, and then the comb and needle are swung toward each other to compress the hair therebetween. The comb is now drawn toward the end of 65 the strand of hair as in the usual manner of combing. After the strand of hair has been combed smoothly, a piece of paper or gauze is placed on the ends of the hair, and then the ends of the hair are placed on the spool and wound thereon.

70 As the operator winds the hair on the spool, the combing action is repeated and this will keep the hairs in the strand in their proper places, and will cause the shorter hairs to be fed into the spool at the proper time.

75 The combing operation is repeated as often as is necessary until all of the hair is evenly distributed and all of the loose ends and bulky hair is wrapped firmly around the spool. One feature of the invention lies 80 in the fact that the comb can be carried entirely around the spool with the hair and then withdrawn by first allowing the comb portion 8 to be urged away from the needle 1 by the spring 10, and then the needle is 85 moved in a longitudinal direction, which is parallel with the axis of the spool. The needle is small enough in diameter so as not to interfere with the tight winding of the hair around the spool. As the operator continues 90 to roll the strand of hair on the spool, he may reverse the position of the comb and use the double needle end to pick up any loose hair ends and to equally distribute this hair. The double needle end of the comb may also be 95 used in wrapping the hair around the spool. The operator, in following out the above steps, will be able to wind the strand of hair tightly and evenly around the spool.

If the operator wishes to use the needles 100

6 and 1 in place of the comb and needle he can just reverse the device and it will function in exactly the same manner as that described for the comb and needle.

5 Although I have shown and described one embodiment of my invention it is to be understood that the same is susceptible of various changes and I reserve the right to employ such changes as may come within the scope 10 of the claims hereto annexed.

10 I claim:

1. A comb comprising a needle, a U-shaped member hinged to the needle and having teeth therein, and a spring for yieldingly holding the member at an angle to the needle.
- 15 2. A comb comprising a needle, a U-shaped member hinged to the needle and having teeth therein, and a spring for yieldingly holding the member at an angle to the needle,
- 20 3. A comb comprising a needle, the teeth on the U-shaped member straddling the needle when the two are swung toward each other.
- 25 4. A comb comprising a needle, and a comb-shaped member attached thereto.
- 30 5. A comb comprising a needle, a comb-shaped member pivoted to the needle, and spring means for swinging the comb away from the needle.

NICHOLAS SAMANTAS.
